(57) **CLAIM**

The ornamental design for a display screen or portion thereof with graphical user interface as shown and described.

DESCRIPTION

The FIGURE is a front view of a display screen or portion thereof with graphical user interface showing the claimed design.

The outermost broken line in the FIGURE shows a display screen or portion thereof and forms no part of the claimed design. Other broken lines in the FIGURE show portions of the graphical user interface or computing device that form no part of the claimed design.
